GUN LOCK

Donald J. Garretson, Detroit, Mich.

Application July 31, 1948, Serial No. 41,740

4 Claims. (Cl. 42—70)

1

My invention pertains to a gun lock and more particularly to a gun lock for short barreled firearms such as revolvers and pistols, so that these may be rendered safe from unauthorized use.

It is an object of my invention to provide a gun lock which may easily be applied to lock a firearm and which may be easily and quickly removed by an authorized person, when the use of the gun is desired.

It is also an object of my invention to provide such a gun lock of a simple and rugged construction which is reliable in use.

It is a further object of my invention to provide such a gun lock which is a unitary structure having no separable parts which have to be brought together for use and which could be separated and lost.

Another object of my invention is to provide such a gun lock which is installable and removable entirely from the muzzle end of the barrel of the gun.

My invention, however, will be more readily understood, and additional objects and advantages thereof will become apparent, by reading the following specification in conjunction with the appended drawings, wherein:

Fig. 1 is a side elevational view showing a revolver with my gun lock installed to prevent unauthorized use, and the inner portion being shown dotted;

Fig. 2 is a side elevational view showing the gun lock by itself, partially broken away and sectioned, and internal parts being shown by dotted lines;

Fig. 3 is an elevational view showing the outer end of the gun lock;

Fig. 4 is an enlarged fragmentary view showing the inner or locking end of the gun lock and the cooperative elements thereof, with dotted lines showing the projected position of the locking members; and

Fig. 5 is an enlarged end elevational view of this inner end of the gun lock.

Referring more specifically to Figs. 1 and 2 of the drawings, I have illustratively disclosed an embodiment of my invention, which comprises an outer lock casing 11, which houses outer or manual lock means 13, and a tubular sheath 15 extending therefrom for insertion through the muzzle end of the barrel 17, of a firearm 19. Although the gun 19 is shown as a conventional revolver, it will be understood that it could be an automatic pistol, single shot pistol, or other type of gun.

To hold the inserted lock sheath 15 in the bar-

rel, as shown in Figs. 2, 4 and 5, the sheath is provided near its inner or inserted end, with a pair of holes 21 in aligned relation in the opposite sidewalls thereof for receiving the opposite ends of a transverse locking pin 23 disposed slidably therein.

This locking pin 23 is easily and quickly projected or retracted by rotating a lock rod 25 extending in the tubular sheath and which has an eccentric pin 27 projecting from the inner end of the rod. The lock pin 23 is provided with an oval aperture 29 for receiving this eccentric pin 27 and by turning the lock rod 25 through about one half a turn, or 180 degrees, the lock pin is either retracted or projected, as more clearly shown in Figs. 4 and 5, where the projected position is represented in dotted lines.

The manual or outer lock means 13, housed in the outer lock casing 11, may for example be a conventional tumbler cylinder which is unlocked and rotated by a proper key 31 inserted therein, in a well known manner. The inner end of the rotative lock cylinder 13 is attached to the outer end of the lock rod 25, as by welding, or in any suitable manner, and in this manner the lock rod is rotated in either direction for projecting or retracting the lock pin, as desired. Other types of key, or even combination locks, may be utilized, as will be understood.

30 The lock rod and its outer sheath are easily made in any suitable length in accordance with the length of the barrel of any firearm for which the gun lock is provided, as will be readily understood. The length of these parts is so selected that the lock pin will be inserted in to a point just beyond the shoulder 33 of the enlarged counterbore comprising the shell chamber 35, shown dotted in Fig. 1. Any attempt to withdraw the device from the gun, without first properly unlocking it and retracting the transverse lock pin, will cause this pin to engage and jam against this shoulder thereby preventing the withdrawal of the device from the gun barrel. The tubular sheath may be made of some soft metal, such as aluminum, or it may be coated with any suitable plastic composition or other material for protection of the inner surfaces of the gun barrel.

It is apparent that within the scope of my invention modifications and different arrangements may be made other than herein disclosed, and the present disclosure is illustrative merely, the invention comprehending variations thereof.

What is claimed as the invention is:

1. A firearm lock comprising, a lock sheath of 55 length suitable to be inserted into a gun barrel

through the muzzle of the barrel, inner lock means adapted to be projected from the inner end of said sheath for locking it into a gun barrel by engagement with the shoulder of the cartridge chamber of the gun barrel, a lock rod extending operatively in said sheath for actuating said lock means, and manual lock means on the outer accessible end of said lock sheath for actuating said inner lock means to lock the device in a gun barrel or to release it therefrom.

2. In a firearm lock the combination of, a tubular sheath comprising an inner end and an outer end and adapted to be inserted into a gun barrel from the muzzle end thereof, manually operative lock means on the outer end of said sheath, inner lock means on the inner end of said sheath for locking it in a gun barrel by engagement with the shoulder of the cartridge chamber of the gun barrel, and means extending through said sheath for operating the inner lock means from the manual lock means for conveniently locking the sheath into a gun.

3. In combination in a firearm lock, a tubular sheath adapted to be inserted into a gun barrel from the muzzle end and of a length such that when so inserted the inner end will be passed in beyond the shoulder of the enlarged cartridge chamber in said barrel, inner lock means on said inner end of the sheath adapted for projection to engage such a shoulder to hold the device in a gun barrel or for retracting to permit removal therefrom, manual lock means on the outer end of said sheath for convenient operation by an authorized person, and actuation

means connecting operatively from said manual lock means through said tubular sheath to said inner lock means whereby said inner lock means is conveniently controllable from the external manual lock means.

4. A firearm lock comprising, a tubular sheath of a diameter suitable to be inserted into the muzzle end of a gun barrel of a certain caliber and of a length such that when so inserted the inner end will be passed in beyond the shoulder of the cartridge chamber of said barrel, a lock pin slidably disposed in the inner end of said sheath for projection laterally to engage said shoulder to hold the device in a gun barrel, manual lock means on the outer end of said sheath for convenient operation by authorized persons, a rod extending rotatively through said sheath for operative connection between said manual lock means and said lock pin, the inner end of said rod being terminated adjacent said pin and having a crank pin projecting eccentrically therefrom into operative connection with a recess in said pin for projecting or retracting said lock pin in accordance with the operation of said manual lock means.

DONALD J. GARRETSON.
